UNITED STATES PATENT OFFICE.

ISAC P. SIGGINS AND JAMES E. COOPER, OF PERRY, NEW YORK, ASSIGNEES TO ROBESON CUTLERY COMPANY, OF PERRY, NEW YORK, A CORPORATION OF NEW YORK.

KNIFE-HANDLE AND METHOD OF MAKING THE SAME.

1,186,693.

Specification of Letters Patent.

Patented June 13, 1916.

Application filed June 17, 1913. Serial No. 774,103.

To all whom it may concern:

Be it known that we, ISAC P. SIGGINS and JAMES E. COOPER, of Perry, in the county of Wyoming and State of New York, have invented certain new and useful Improvements in Knife-Handles and Methods of Making the Same; and we do hereby declare the following to be a full, clear, and exact description of the same, reference being had to the accompanying drawings, forming a part of this specification, and to the reference-numerals marked thereon.

Our present invention relates to the manufacture of handles for knives and similar hand implements, and is more particularly adapted to the manufacture of handles for pocket knives, and it has for its object to provide a simple method of securing malleable or slightly malleable handle plates to knife scales or to the corresponding element in the structure of the implement.

A further object of the invention is to produce a slightly, strong and durable handle that may be produced rapidly and cheaply in large numbers by a simple method and particularly one in which the handle plates are composed of paper or fiber, the invention being directed in part more particularly to the fastening of handles of this particular composition onto the knife scales.

To these and other ends the invention consists in certain improvements and combinations of parts all as will be hereinafter described, the novel features being pointed out in the claims at the end of the specification.

In the drawings: Figure 1 is a plan view of the female member of a die couple such as we prefer to use in the practice of our invention; Fig. 2 is a central longitudinal section therethrough, showing a portion of a completed knife handle therein; Fig. 3 is a transverse section through both die members taken substantially on the line 3-3 of Fig. 2, but showing the knife handle in cross section previously to the pressing operation; Fig. 4 is a view similar to Fig. 3 showing the positions of the same parts at the completion of the pressing operation; Fig. 5 is a plan view of a knife scale blank such as the invention contemplates; Fig. 6 is a plan view of the handle plate blank; Fig. 7 is a plan view of the finished handle, and Fig. 8 is a perspective view of the scale

plate of a finished handle with the handle plate omitted.

Similar reference numerals throughout the several figures indicate the same parts.

The construction of knife handles in accordance with the present invention may be readily accompanied by a coincident embossing of the handle in accordance with features of the invention set forth in our previous and co-pending application, Serial No. 768,123, filed May 16, 1913, and we have hence illustrated it herein in connection with an embossing die such as there shown and described. As stated in that application, aside from the cost of the material itself, one of the chief objections, from a manufacturing standpoint, to the use of bone, horn and other similarly frangible substances as handle plates for pocket knives and similar implements is that there is a considerable percentage of loss and waste due to the cracking or chipping of the handle plate both in the course of manufacture and subsequently when the knife is in use. In the factory, the application of the rivets commonly used to hold the knife together and to secure the handle plates thereon is perhaps the most frequent cause of this chipping and breaking, whereas the handle plate of the finished knife will often crack from simply being dropped upon a hard surface. By the practice of our present invention, handle plates may be made from paper to constitute indestructible and more securely fastened elements of the knife structure with or without a coincident embossing operation in imitation of the less serviceable and relatively expensive materials above mentioned as provided for by the invention of our other application referred to, but a substantially different method of securing the handle plate in position is contemplated by this invention whereby a different style of handle may be produced from that previously disclosed by us.

Referring more particularly to the drawings, 1 indicates the scale plate of a pocket knife to which the handle plate is directly connected and between a pair of which the springs, blades and linings are comprised. This is usually constructed of a relatively thin piece of brass, steel or other sheet metal with or without bolsters 2 at the ends thereof. The handle plate 3 preferably corresponds in outline to the scale plate or, at

least, to that portion comprised between the bolsters 2 upon which it is superposed and we prefer to use as the material thereof hard black paper or what is known as "commercial fiber," the substance of this nature largely used in electrical apparatus as an insulating material being eminently suitable. While held together in superposed relationship, the two plates are placed beneath a suitable punching die (not shown) with the scale plate 1 uppermost and a plurality of securing projections such as the spurs indicated at 4 in Figs. 2, 3, 4 and 8 are struck up from the body thereof and at the same time driven and embedded into the material of the handle plate 3 in which cavities for the reception of the spurs are thereby simultaneously formed.

Though a relatively hard substance, this fiber possesses sufficient malleability to permit of such impressions being made therein with the application of sufficient power, and because of its extreme toughness and durability there is no accompanying tendency to crack or break. The spurs 4 are disposed angularly when completed so as to present an undercut surface at 5 and the material of the handle plate 3 in fact possesses just that slight degree of elasticity after the impact of the punching blow to react slightly and grip the spurs with a retaining pressure which is sufficient to hold them in under ordinary circumstances with the aid of the bur that is left on their edges by the punching operation.

We prefer not to rely, however, merely upon the fastening thus far described but arrange for a more thorough and positive interlocking of the two plates which is accomplished by a further operation that may or may not comprise the act of embossing the handle plate as well in the manner set forth in our application above referred to. But it may well accompany this operation in which case the two plates 1 and 3 connected by the spurs are laid with the handle plate 3 lowermost within the cavity of a female die block 6 having an embossing surface 7 at the bottom thereof and inclined side walls 8. At this point, the handle plate 3 lies well above the surface 7, as shown in Fig. 3, its corners resting on the inclined or tapered sides of the cavity. A male die 9 closely fitting the cavity is then brought down and the scale plate 1 and handle plate 3 driven down together flatwise to the bottom of the cavity as shown in Fig. 4 and compressed between the die members under extreme pressure, say in the neighborhood of twenty tons to the square inch, or sufficient to imprint the design 7 upon the under face of the blank 3. Simultaneously with this action the edges of the handle plate 3 are forced inwardly from the side by reason of the tapered walls 8 of the die cavity with

the result that the whole plate is subjected to great general internal and external pressure. Its density is increased and the slight malleability it possesses allows a displacement or flow of the material back within the cavities formed by the securing projections or spurs 4 as indicated at 10 in Fig. 4 and an interlocking thereof beneath the undercut surfaces 5 of the spurs. The intimate association of the two plates established by the pressure is thus rendered permanent aside from the other advantageous results obtained with particular reference to the handle plate 3 itself for a full understanding of which reference is again directed to our prior application in which it is more minutely described and claimed.

The securing spurs or projections 4 need not and preferably do not extend entirely through the handle plate 3 and in the event that the embossing operation is joined with the securing operation, as shown in the present embodiment, the exterior surface of the handle plate is in no way mutilated.

Of course, other materials possessing the same or a greater degree of malleability may be used for the handle plate in the practice of our invention, but in view of the extreme durability of the fibrous material suggested; its cheapness and its capability of taking the embossings and of taking a good polish or finish we prefer to use this particular material which, we have discovered, possesses hitherto unrecognized characteristics permitting its use in such capacities and under such treatment. It may be said at this point that in order to increase the ductility of the fibrous material the blanks 3 are preferably heated just prior to their introduction between the dies and pressed out while hot or, if desired, the dies themselves may be heated.

We claim as our invention:

1. A method of securing fiber handle pieces upon knife scales which consists in superposing a metal scale plate upon the handle plate, in then punching out an oblique angularly disposed spur having an undercut surface from the body of the scale plate at a point removed from its edges and simultaneously embedding it in the material of the handle plate and in then subjecting the handle plate to sufficient simultaneous flatwise and edgewise pressure to compress and flow the fibrous material thereof beneath the undercut portion of the spur and cause it to interlock therewith against withdrawal of the spur.

2. As an article of manufacture, a knife handle comprising a scale plate and a handle plate of fibrous material, the latter having embedded therein an angularly disposed spur struck out from the material of the scale plate at a point removed from its edges to produce an undercut portion be-

neath which the fibrous material has been flowed or compressed to produce an interlocking relationship.

3. As an article of manufacture, a knife handle comprising a scale plate and a handle plate of fibrous material, the latter having embedded therein a spur that has been struck out from the material of the scale plate at a point removed from its edges and

simultaneously driven into the material of the handle plate without extending completely through the latter.
